COTTON PICKING MACHINES AND THE LIKE
William F. Lee, Glendale, and Joseph B. Allen, Spartanburg, S.C., assignors to W. Avery Quinn, Converse, and W. J. Wyatt, Spartanburg, S.C.

Filed Nov. 4, 1960, Ser. No. 67,374
12 Claims. (Cl. 242—55.1)

Our invention relates to improvements in cotton picking and analogous machines used by the textile industry, and has particular reference to the lap roll forming means thereof.

Picking machines, according to known and usual operation of textile mills, are employed to make uniform webs or bats known as picker laps, which are removed from the machine in the form of large rolls and are subsequently to be used as feed material for carding machines.

In the final, or lap roll forming, operation of the usual picking machine, the aforementioned picker laps are wound onto a cylindrical core, customarily referred to as a "pin." This core-providing pin is floatingly carried by so-called "cheeks" which are usually removable and rise from opposite sides of the picker machine frame, said pin and the subsequently formed lap roll thereon being supported and frictionally rotated by subjacent laterally spaced driven rolls.

Heretofore when a lap roll of predetermined size has been formed and removed from the picking machine, considerable time and manual labor is required to properly position the heavy core pin, for a succeeding lap roll, in the side cheek-provided guides above and in engagement with the aforementioned driven rolls. Also, before installation, each core pin has to be properly coated throughout its length and diameter, with an oil film so that the cotton or other lap delivered to it will be readily picked up and wrapped theraround to start a lap roll. Owing to the size and weight of the core pin, proper oiling of same has been an unhandy and time consuming operation.

Therefore, the present invention has among its primary objects to (1) provide cheek-carried means to support and effect the automatic oiling of the next to be used core pin during the rearward doffing movement of a completed roll form lap; and (2) to provide for automatic non-manual means for properly locating a previously oiled core pin in lap roll-starting position immediately a completed lap roll has been doffed. Thus, the invention is calculated not only to save labor, but also to speed up production, and the latter particularly since no time is lost due to lap roll doffing.

Another important feature of the invention is the provision of floating means for pressing against and, in effect, ironing the lap roll being formed, so as to guard against so-called "splits" and bad selvage. This "ironing" means preferably takes the form of the weighty next-to-be used core pin which is rollingly supported by rearwardly and upwardly inclined portions of the novel side cheeks, which constitute an important feature of the instant invention.

Additionally, the invention contemplates, as the previously mentioned core pin oiling means, a lubricant dispensing connector for the aforementioned side cheeks.

Invention also resides in various novel features of construction, combination, and arrangement, and in modes of operation of the various parts of the now preferred embodiment of our advance in the art which is shown in the accompanying drawing, the advantages of which will be readily apparent to those versed in the art. However, the drawing disclosure should be taken as illustrative rather than limitative since our invention concept is obviously susceptible of other mechanical expression within the spirit and scope of the subject matter claimed hereinafter.

In the drawing, wherein the same reference characters

2

have been used to designate the same parts wherever they appear in the several views.

FIG. 1 is a fragmentary side elevational view, partly in section, of the lap roll-forming rear end of a picker machine embodying our invention, but with certain conventional elements such as the lap supply means of FIG. 1A deleted;

FIG. 1A is a fragmentary longitudinal sectional view of a standard picker machine having conventional side cheeks, a lap roll being illustrated in the process of formation;

FIG. 2 is a broken view illustrating the FIG. 1 structure in top plan; and

FIG. 3 is a sectional view taken on the line 3—3 of FIG. 1 illustrating the support means for one of the yielding cheek-carried core pin buffers of FIG. 1.

Referring to the drawing by reference characters and turning, for background purposes to FIG. 1A, it will be noted that this view illustrates the lap roll forming rear end of a conventional cotton picker. Here, the loose fibre-defined web or batt 6 is shown to be delivered, as usual, from condenser cylinders 7 by way of the familiar compressor rollers 8 to conventional parallel and adjacent driven rolls 9 for the formation of the superjacent roll 25 form lap 6a about the core pin 10.

Still referring to the conventional picker of FIG. 1A, it will be understood that the core pin 10, with its ends in the cheek 11 provided slots 12, initially rests upon rolls 9 to be frictionally rotated thereby as is also the subsequently formed lap 6a. In accordance with standard practice, the core pin 10 is oil coated to facilitate its pick up of fibrous web or batt 6 delivered thereto by rolls 9.

Instead of our novel presently to be described cheek plates, the art machine of FIG. 1A discloses the aforementioned conventional cheeks 11 as rising from opposite sides 14 of the picker frame in opposition to the ends of the roll-form lap 6a. When the lap 6a has reached a predetermined size the picker drive means is cut off and the lap 6a is doffed, or taken off of the machine. In carrying out the doffing operation the lap 6a, supported by engagement of the projecting ends of its core pin 10 with the arched rear portions 11b of cheek plates 11, is rolled rearwardly until said core pin ends rest in the cheek-provided rear end seats 13. Later, the completed lap will 45 be removed from seats 13 for storage or for feeding to a carding machine.

But before the conventional picker of FIG. 1A can again be put in operation, a core pin 10 for the next lap 6a must be manually positioned on the driven rolls 9 with 50 its ends in the vertical cheek-provided slots 12. This is very time consuming and since the pin 10 is very heavy, it is a two man job, the necessity for which our invention obviates.

Coming now to what constitutes our invention, and 55 turning to FIGS. 1 and 2, our novel side wall 14 carried cheeks 15 are seen to provide the outwardly extending base flanges 16, the rectangular upwardly projecting buffer member-carrying forward portions 17, and the upstanding laterally spaced and rearwardly extending 60 reserve core pin supporting portions 18 which are of lesser height than the forward cheek portions 17.

As shown in FIGS. 1 and 2, the space between the rear flange-incorporating ends 17a of the forward buffer-carrying cheek portions 17 and the vertical forward ends 65 20 of rear reserve core pin supporting cheek portions 18 cooperate with the base flanges 16 to provide the initial seats 19 for the respective reduced ends 10a of the conventional core pin 10 of the to be produced roll form lap 6a. Thus 20, 20 and the lower portions of 70 17a, 17a form the rear and forward walls, respectively, of seat 19.

It will be understood from FIGS. 1 and 1A that as

the diameter of the driven roll 9, 9 supported and rotated lap 6a increases the core pin 10 rises vertically so that its ends are lifted out of the cheek 15 provided seats 19 of FIG. 1 and 12 of FIG. 1A.

According to the old-in-the-art FIG. 1A structure, the reduced free ends of the rising core pin 10 bear against vertical cheek-provided edges. But in accordance with our invention such ends 10a of the rising core pin 10 bear against the yielding forward cheek portion 17 carried buffer 24. This, buffer 24, along with its functions and advantages, will be referred to in detail later on herein.

In carrying out the invention and after the diameter of lap 6a has so increased that its periphery extends rearwardly of the plane of the rounded forward ends 21a of the reserve core pin-supporting edges 21 of the rear cheek portions 18, as indicated in FIG. 1, novel use is made of a reserve core pin 10'.

The aforementioned reserve core pin 10' which has theretofore been supported in a "ready" position crosswise of the rear end of the picker with its ends in the novel cheek 15 provided seats 23, is now lifted forwardly so that its pintle ends are rollingly supported on the forwardly and downwardly extending top edges 21 of the rear cheek portions 18. This means, as indicated in FIG. 1, that said reserve pin 10' will roll forwardly to bear against the periphery of the rotating roll-form lap 6a, so that the latter will be subjected to an "ironing" action by the heavy reserve pin 10'. This ironing action is very desirable because it is very effective in preventing so-called "splits" and bad selvage in the roll form lap 6a.

The novel means for oil-coating the reserve core pins 10' (which of course are identical with core pins 10), will now be referred to. In this connection it will be noted that the opposed sides of cheek portions 18, at points just short of the upwardly projecting stops 22 at the rear ends of the reserve pin-supporting edges 21, carry the combined lubricant applicator and cheek portion (18) spacer 25.

The combined cheek portion (18) spacer and lubricant applicator 25, as illustrated herein, is a split lubricant and wick-carrying tube having its ends carried by brackets 26 which are adjustably secured as at 27 to the opposed wall surfaces of cheek portions 18. A wick 28 extends outwardly through the tube 25 split, which latter is substantially longitudinally coextensive with tube 25.

In accordance with our invention, a reserve core pin 10' is automatically oiled by the operation of doffing a completed lap 6a from the rear end of the picker. Such rearward movement of the lap 6a brings the reserve pin 10' into rolling contact with wick 28 before its pintle ends reach stops 22, so that an oil film is applied to said pin 10' to facilitate the subsequent picking up of the start of the next lap 6a. By the time the completed lap 6a has been rolled rearwardly over and past the reserve pin 10', the latter has been properly oil coated. After lap 6a has been manually rolled rearwardly over the reserve pin 10' which has been halted by stops 22, said completed lap 6a is either removed from the picker entirely or is located with its core pin ends 10a in the now unoccupied reserve pin seats 23. As soon as the completed lap 6a is out of the way, the reserve pin 10' of course simply rolls down cheek edges 21 against the shock absorbing buffers 24 and into seats 19 for the start of a second roll-form lap 6a. No manual labor or loss of time is involved, and the next lap 6a can be started immediately.

The yielding buffers 24 comprise elongated plates spacedly overlying the rear ends 17a of cheek portions 17 with their lower ends extending into pin seats 19 to spacedly interpose between the heavy traveling replacement pin 10' and the exposed periphery of the forward roll 9. Thus cheek portion ends 17a and the forward roll 9 are protected against shock damage, and the pin 10' against exterior scarring.

Also, when the pins 10, 10' are tubular and have ball races therein to support and facilitate separation of same

from a headed core rod (not shown) then buffer 24 protects the ball race assemblies against damage. However, such a tubular core rod-carrying pin forms no part of the present invention and hence has not been illustrated herein.

Referring to the mounting of yielding buffers 24, FIGS. 1 and 3 show the latter as supported by two vertically spaced and forwardly extending rods 29. These rods 29 pass through edge bearing recesses 30 in the outturned flanges 17x at the rear ends 17a of cheek portions 17 and are guided in bearings 31, 31a carried by the respective vertical outwardly extending and laterally spaced cheek-provided ribs 32, 33.

The buffer carrying rods 29 are urged rearwardly by 15 encircling coil springs 34 interposed between rod-carried stops 35 and the related rib-carried bearings 31a, as indicated in FIG. 1.

For reinforcement purposes, the upstanding buffer (24) carrying portions 17 of the cheeks 15 will have outwardly 20 extending reinforcing top and forward end flanges 17b, 17c, respectively. Also as earlier pointed out, the lubricant applicator 25 functions as a cheek 15 spacer.

From the foregoing, it is believed that the construction, 25 operation, and advantages of the invention will be clear. The removable cheek plates or frame portions 15 are fixedly secured to the flanged tops of the picker side walls 14 in the usual or any preferred way.

Having thus described our invention, what is claimed is.

1. In a picker machine for loose cotton or other fibrous material wherein a sheet form batt is delivered to and wound about a floating and driven core pin to provide a roll form lap, the combination of a frame providing side portions, driven parallel lap rolls carried by said frame side portions and supporting and driving said core pin and the lap roll formed, thereon, opposed cheek portions provided by said frame sides and opposed to the ends of the lap roll to be formed, said cheek portions having open topped seats through which end portions of the core pin extend, said cheek portions providing downwardly inclined top portions extending approximately from the forward end of the frame and communicating with said seats, a core pin for a succeeding lap roll freely supported on said inclined top cheek portions and making ironing engagement with the lap roll being formed, and said succeeding core pin rolling into said seats for supporting and driving engagement with said lap forming rolls upon removal of a completed lap roll, and a transversely extending lubricator for the exterior surface of said second core pin, said lubricator being carried by opposite sides of the picker frame at a point remote from said seats and disposed adjacent the plane of said inclined second core pin-supporting cheek portions so that the second core pin can be rolled thereagainst, the applied oil coating facilitating core pin pickup of the sheet form fibrous material supplied thereto.

2. In a picker machine for loose cotton or other fibrous material wherein a sheet form batt is delivered to and wound about a floating and driven core pin to provide a roll form lap, the combination of a frame providing side portions, driven parallel lap rolls carried by said frame side portions and supporting and driving said core pin and the lap roll formed thereon, opposed cheek portions provided by said frame sides and opposed to the ends of the lap roll to be formed, said cheek portions having open topped seats through which end portions of the core pin extend, said cheek portions providing downwardly inclined top portions extending approximately from the forward end of the frame and communicating with said seats, a core pin for a succeeding lap roll freely supported on said inclined top cheek portions and making ironing engagement with the lap roll being formed, and said succeeding core pin rolling into said seats for supporting and driving engagement with said lap forming rolls upon removal of a completed lap roll, and the opposite cheek

portions of said picker frame sides providing upstanding core pin-opposed edges rising from the seat wall portions which are remote from said inclined roll-supporting side portions and which extend above the latter, and yielding core pin-intercepting buffers carried by said upstanding core pin-opposed edges.

3. The combination set forth in claim 2, and the frame side-provided cheek portions being removable from related frame side portions.

4. The combination of claim 1, and said lubricator including a bar-form member which also functions as a brace between opposite picker sides.

5. The combination of claim 1, and said lubricator comprising a split oil reservoir-providing tube providing bracket-form end closures and a lubricant dispensing wick extending through said tube split for engagement with said second core pin.

6. The combination of claim 2, and said buffers extending into said core pin seats, whereby to protect exposed and adjacent core pin and lap-supporting drive rolls.

7. The combination set forth in claim 2, and said buffers comprising plates, rearwardly extending supporting rods for said plates, picker side wall-provided guide means slidably supporting said rods, and yielding means normally tending to maintain said buffer plates spaced outwardly from said upstanding core pin opposing edges.

8. In a picking machine providing a frame having side members and lap end-opposing cheeks carried thereby, each of said cheeks providing an open topped core pin-receiving seat and rearwardly extending core pin supporting edge leading thereto; the combination of a cheek carried core pin lubricator adjacent the plane of said core pin supporting edges and located rearwardly of said seats, whereby a core pin can be lubricated before disposition in said seats.

9. The combination of claim 8, and core pin supporting edges being downwardly inclined in the direction of said seats.

10

5

10. The combination of claim 8, and core pin supporting edges being downwardly inclined in the direction of said seats, there being core pin intercepting stops at the rear ends of said inclined core pin supporting edges, and the rear end of each cheek providing a reserve core pin-receiving seat rearwardly of said stops.

11. The structure of claim 8, and the rearwardly extending core pin-supporting cheek edges providing upstanding stops rearwardly of said lubricator, whereby a next-to-be used core pin, rolling on said edges, will be actuated rearwardly to be oil coated by said lubricator in the rearward doffing movement of a completed lap before engaging said stops.
